UNITED STATES PATENT OFFICE.

GEORGE G. GREENBURG, OF CHICAGO, ILLINOIS.

DESIGN FOR A BADGE.

No. 40,072.

Specification for Design.

Patented June 22, 1909.

Application filed April 21, 1909. Serial No. 491,391. Term of patent 7 years.

To all whom it may concern:

Be it known that I, GEORGE G. GREENBURG, a citizen of the United States, residing at Chicago, in the county of Cook and State of Illinois, have invented a new, original, and ornamental Design for Badges, of which the following is a specification, reference being had to the accompanying drawing, forming part thereof.

The drawing is a face view of a badge embodying the new design.

The badge is characterized by having displayed thereon a representation of the ancient god, Mercury, and an encircled star as shown in the drawing.

I claim:

The ornamental design for a badge as shown and described.

GEORGE G. GREENBURG.
